UNITED STATES PATENT OFFICE.

PATRICK CONNELLY, OF ROCHESTER, NEW YORK.

CHILL FOR CAR-WHEELS.

SPECIFICATION forming part of Letters Patent No. 427,052, dated May 6, 1890.

Application filed March 5, 1890. Serial No. 342,715. (No model.)

To all whom it may concern:

Be it known that I, PATRICK CONNELLY, a citizen of the United States, residing at Rochester, in the county of Monroe, in the State 5 of New York, have invented certain Improvements in Chills for Cast-Iron Car-Wheels, of which the following is a specification, reference being had to the accompanying drawings.

10 My invention relates to certain improvements in the construction of chills for cast-iron car-wheels, which improvements are fully described and illustrated in the following specification and accompanying drawings, the 15 novel features thereof being specified in the claims annexed to the said specification.

My improvements in chills for car-wheels are represented in the accompanying drawings, in which—

20 Figure 1 is a partial plan view showing a wheel or the pattern in place in the chill. Fig. 2 is a transverse section of the chill and wheel or pattern. Fig. 3 represents one of the radial plates detached in elevation. Fig. 4 is a section of one of the plates on the line 4-4, Fig. 3. Fig. 5 is a section on the line 5-5, Fig. 3.

In the construction of my improved chill for car-wheels I prepare a suitable number of cast-iron radial plates A, and after arranging 25 them in a circle, as indicated in Fig. 1, I cast an iron ring B around them while inclosed in suitable clamps, and subsequently finish the chill in a suitable lathe by turning the inner edges of the plates to the form adapted 30 to give the proper shape to the tread and flange of the wheel. As indicated in Figs. 1 and 4, the radial plates are beveled or wedge-shaped, so that they receive support from each other. Any suitable number of radial 35 plates may be used in any one chill, according to the thickness of the plates, which may vary from one-quarter to five-eighths of an inch on their inner edges. In assembling the plates into the circular form the last plate is 40 driven in firmly by any suitable means, so as to insure actual contact between the sides of all the plates. When assembled in a suitable ring, and while clamped between suitable clamp-plates, the plates are inserted in a 45 suitable mold and the ring B cast around them. As indicated in Fig. 2, the ring B is preferably of U shape in section, so as to

hold the plates in place and firmly in contact with each other. The sides of the plates where the ring is cast upon them may be 55 straight, as indicated at C, Fig. 3, although I prefer to provide them with a recess, such as D, Fig. 3, into which the ring projects. As the ring B contracts after casting, the plates are pushed against each other with great 60 force. After the ring has been cast around the radial plates the chill is finished and made ready for casting car-wheels therein by turning the inner edges of the plates to the form desired for the flange and the tread. 65

The chill may be made of any desired size, and is used with the cope and drag in the same way as the ordinary solid chill.

The surfaces of the plates where they bear against each other are preferably dressed on 70 one side at least, and in order to facilitate this operation I provide the plates on one side with the projecting surfaces or facing-strips E, which reduce the amount of metal necessary to be ground away when the plates 75 are trued up, which is most conveniently effected on the flat side of an emery-wheel. The depressions F between the raised surfaces also facilitate the escape of the gases formed in pouring the wheel. The plates 80 may, however, be used without the depressions F.

The outer ends of the radial plates are preferably made of a reduced depth, so that the sides of the ring B come flush with the 85 upper and lower surfaces of the chill.

By the use of my improved chill cast-iron car-wheels can be cheaply made perfectly true and entirely free from the ordinary defects—such as chill-cracks and sweat-spots—as 90 I have demonstrated by practical experience extending over a considerable period of time.

I claim—

1. The herein-described chill for cast-iron car-wheels, consisting of a series of wedge-shaped plates arranged in a circle, with their radial surfaces in contact, having their inner ends of a form corresponding with the tread and flange of the wheel and secured together by a ring cast around their outer ends, substantially as described. 95

2. The combination, with a series of wedge-shaped chill-plates A, dressed on one radial surface and arranged in a circle, with their 100

radial faces in contact, of the ring B, cast around the outer ends of the plates, substantially as described.

3. The combination, with a ring of wedge-shaped radial chill-plates A, having dressed facing-strips on one radial surface, of the ring B, cast around the outer ends of the plates, whereby their radial surfaces are held in close contact, substantially as described.

4. The combination, with a ring of wedge-shaped radial chill plates, having their outer ends of reduced depth, of the ring B, cast about the reduced ends of the plates, substantially as described. 10

PATRICK CONNELLY.
